UNITED STATES PATENT OFFICE.

JAMES S. FOWLER, OF PEORIA, ILLINOIS.

IMPROVEMENT IN CORN-SHELLERS.

Specification forming part of Letters Patent No. 35,227, dated May 13, 1862.

To all whom it may concern:

Be it known that I, JAMES S. FOWLER, of Peoria, in the county of Peoria and State of Illinois, have invented a new and Improved Machine for Shelling Corn; and I do hereby declare that the following is a full, clear, and exact description of the same, reference being had to the accompanying drawings, making a part of this specification, in which—

Figure 1 is a longitudinal vertical section of my invention taken on the line $x x$, Fig. 3; Fig. 2, a detached side view of a feeder pertaining thereto; Fig. 3, a plan or top view of the invention.

Similar letters of reference indicate corresponding parts in the several figures.

This invention relates to a new and improved machine for shelling corn and separating the corn from the cobs; and it consists in the employment or use of an elastic or yielding concave screen in connection with a rotary shelling-cylinder, discharging-apron, and a shoe provided with a screen or screens, and also in connection with spiral or screw conveyers, as hereinafter described.

To enable those skilled in the art to fully understand and construct my invention I will proceed to describe it.

A represents a case or box, which is placed on a frame, B, mounted on wheels for the ready conveyance of the machine from place to place, and C is a cylinder, which is placed transversely on the upper part of the case A and is provided with teeth a . The journals of the cylinder C are fitted in boxes D, which are adjustable vertically in the sides of the case A; and directly underneath the cylinder C, within the case A, there is placed a slotted or grated concave, E, which is formed of rods b , the ends of which are fitted in curved bars c , connected together by joints d , which are formed by the rods b , which are in line with the lapped ends of the bars c , passing through said ends. These rods b , which form the pinnacles of the joints, pass through the sides of the case A and rest upon spiral springs e , which admit of the concave having a yielding movement. This yielding movement is still further assisted by having the upper innermost end, b , of the concave connected to spiral springs f .

F F are inclined boards or chutes, which

are placed in the case A, underneath the concave E, and serve to guide the shelled corn upon a screen, G, which is underneath the concave and in a shoe, H. (See Fig. 1.) The front part of the shoe H is attached to the sides of the case A by pivots g , and its back part is suspended by rods I I from cams $h h$ on the ends of the shaft of the lower roller, J, of the discharging-apron K, a rod, I, being at each side of the discharge end or back part of the shoe.

The discharging-apron K is formed of slats h , having their ends fitted on chains $i i$, which pass around the roller J and around a roller, L, in the upper part of an inclined box, M, which is attached to the case A, the bottom j of box M serving as a guide to conduct the grain which may pass through the apron K to the screen G.

N is a rotary fan which is fitted in a case, O, attached to the front end of case A. The case O forms the greater portion of a hollow cylinder, as shown in Fig. 1, and to its lower end there is attached by hinges k a flap, P, which extends the whole length of the fan-case and has pins projecting laterally from its front edge—one at each side—said pins passing through vertical oblong slots m in the sides of the case and admitting, by means of wedges or keys inserted in said slots, the flap P being more or less inclined in order to regulate the direction of the blast from the fan N.

Power is applied to the discharging-apron K by a belt passing around a pulley, Q, on one end of the shaft of the upper roller, L, of the discharging-apron, and power is applied to the cylinder C and fan N by belts passing around pulleys R S at one end of their shafts.

T is a conveying-screw which is placed in a trough, U, at the lower end of an inclined board or chute, V, in case A. The trough U is placed transversely in the case A, and the screw T may be rotated by a belt from one end of the fan-shaft, said belt passing over pulleys W W. (See Fig. 2.) The trough U is slightly inclined and its lower or depressed end communicates with an inclined trough, X, which is at one side of the case A, and has an elevating-screw, Y, placed in it, which is driven by a belt passing around a pulley, Z, at the upper end of the shaft of screw Y.

The upper end of the trough X is forked or divericated, as shown at $a^x a^x$ on Fig. 2.

A', Fig. 3, is an endless feeding-apron, which is formed of slots o, attached transversely to a canvas apron, p, said apron passing around rollers q q at the ends of a case, B', which is formed of two parts connected by joints r. When the machine is not in use, the case B' may be folded so that it will not monopolize much space, and when the machine is in use the case B' is attached in any proper way to the front end of the case A, so as to feed the ears of corn between the cylinder C and concave E.

The operation is as follows: The machine may be driven by any convenient power and the ears of corn are fed between the cylinder C and concave E, the former being adjusted to the desired height in consequence of its journals being fitted in adjustable boxes D. The corn is shelled from the cobs by the action of the toothed cylinder C, the ears of corn being kept in contact with the cylinder by means of the concave E, which, in consequence of being allowed to yield or give, owing to its jointed form and the application of the springs, as described, will accommodate itself to the different sizes of the ears. The shelled corn passes down through the concave E on the screen G, which has an up and down shake-motion given it by means of the rods I I and cams h h. The coarse foreign substances pass off the depressed end of the screen G, while the corn passes through it and is subjected to a blast from the fan N, the direction of which is regulated by adjusting-flap P, and which blast deprives it of all light foreign substances. The corn falls on an inclined board, N', which conducts it into the trough U, and the conveying-screw T discharges the corn into the lower end of the

trough X, and is carried up in said trough by the screw Y and discharged from its ends $a^x a^x$. The cobs are carried up and discharged from the machine by the apron K. Any loose grains of corn which may be mixed with cobs fall through the apron K and are conveyed down to screw G by the inclined bottom j. A grating, C', is attached to the inner end of the concave to admit of the cobs passing on the lower part of the apron K.

This invention effects a thorough separation of the corn from the cobs and at the same time shells the corn thoroughly from the cobs, and is capable of being adjusted to shelling ears of various average sizes of different kind of corn, and also of adapting itself to ears of different sizes in the same kind of corn.

I do not claim separately the employment or use of conveying-screws, for they have been previously used; but,

Having thus described my invention, what I do claim as new, and desire to secure by Letters Patent, is—

1. The toothed cylinder C, in combination with the jointed and yielding slotted or grated concave E, screen or screens G, with a shake-motion given it, as described, and the endless discharging apron K, all arranged for joint operation, as and for the purpose herein set forth.
2. The combination of the screws or spiral conveyers T Y with the cylinder C, concave E, screen or screens G, fan N, and discharging-apron K, and feeding-apron A', all arranged as and for the purpose set forth.

JAMES S. FOWLER.
